UNITED STATES PATENT OFFICE.

ARTHUR L. SCHOOLER, OF CINCINNATI, IOWA.

EGG-TESTER.

1,148,997.

Specification of Letters Patent.

Patented Aug. 3, 1915.

Application filed March 13, 1915. Serial No. 14,201.

To all whom it may concern:

Be it known that I, ARTHUR L. SCHOOLER, a citizen of the United States, residing at Cincinnati, in the county of Appanoose and State of Iowa, have invented certain new and useful Improvements in Egg-Testers, of which the following is a specification, reference being had to the accompanying drawings.

10 This invention relates to certain improvements in egg testers and it is an object of the invention to provide a novel and improved device of this general character including an illuminating means under control 15 of the eggs to be tested or candled.

Furthermore, it is an object of the invention to provide a novel and improved device of this general character including a minimum of parts affording a maximum of efficiency and which may be readily assembled 20 into operative relation with convenience and facility.

The invention consists in the details of construction and in the combination and arrangement of the several parts of my improved egg tester whereby certain important advantages are attained and the device rendered simpler, less expensive and otherwise, more convenient and advantageous for use, 30 all as will be hereinafter more fully set forth.

The novel features of the invention will be carefully defined in the appended claims.

In order that my invention may be better understood, I will now proceed to describe the same with reference to the accompanying drawings, wherein—

Figure 1 is a vertical longitudinal sectional view taken through an egg tester constructed in accordance with an embodiment of my invention; Fig. 2 is a transverse sectional view taken through the device as herein embodied; Fig. 3 is a fragmentary perspective view of the upper portion of 40 my improved tester with the hood in operative position; and Fig. 4 is a fragmentary view in top plan of the table herein included.

As disclosed in the accompanying drawings, 45 1 denotes a container of predetermined configuration and dimensions in which the batteries B may be positioned. The side walls of the container 1 have se-

cured to the interior faces thereof the horizontally disposed cleats 2 at a point intermediate the height of the container and 55 adapted to serve as a support for the removable tray 3.

Yieldably supported above the tray 3 under the influence of the expandable members 4 is the table 5, said expandable members 4 60 being herein disclosed as conventional coil springs interposed between the tray 3 and the table 5 and suitably affixed thereto and of such a tension as to permit a depression of the table under the influence of the eggs 65 to be tested when applied to said table. The table 5 has produced at substantially its axial center the egg receiving openings 6 preferably six in number and so positioned one relative to the other as to permit the 70 insertion therein or removal therefrom of three eggs at one operation as in the testing of eggs, it is customary for the operator to handle three eggs with one hand at a single operation.

75 Secured to the tray 3 directly below the egg receiving openings 6 is a reflector 7 at the axial center of which is positioned the illuminating member 8, herein disclosed as an incandescent electric lamp, preferably of 80 six candle power, and secured in a conventional manner within the socket 9 secured to the tray 3.

The socket 9 is in electrical connection with the source B through the conductor *a* 85 and with the spring contact 10 through the conductor *b*, said spring contact 10 being carried by the tray 3 and projecting thereabove and adapted to be engaged by the spring contact 11 depending from the table 90 5, said spring contact 11 being in electrical connection with the source B through the medium of the conductor *c*, said conductor *c* having interposed therein the circuit closer 12 of conventional construction and preferably positioned exteriorly of the container 1 so that the device may be rendered inoperative when desired. It is also to be observed that the conductors *a* and *c* are of such a length as to permit the tray 3 and its con- 95 comitant parts to be readily removed from within the member 1, when the necessities of practice so require.

Upon the insertion of the eggs within the

openings 6, the table 5 will move downwardly sufficiently to cause an engagement between the contacts 10 and 11, whereby the tray 8 will be caused to be illuminated, and 5 upon the removal of the eggs the table 5 will automatically elevate under the expandable members 4 sufficiently to break the engagement between the contacts 10 and 11.

The upper face of the base 1 is open and 10 coacting therewith is the hood 14 preferably in the shape of an inverted V in cross section, and having the lower marginal portion of one of its side walls 15 cut away, as at 16, entirely therealong, to provide means where- 15 by the eggs may be readily applied to or removed from operative position upon the table 5 and to permit visual access within the container 1, said visual access being further facilitated by the recess 17 produced 20 in the lower marginal portion of the side wall 15. The opposite side wall 18 of the hood is hingedly connected with the upper marginal portion of an adjacent side wall of the container 1, at 19, said hood being 25 adapted to be thrown back entirely free of the top of the container 1 so that it will offer no obstruction to the insertion or removal of the tray 3 and its concomitant parts. I also find it of advantage to have coacting 30 with the container 1 and the hood 14 the chain 20 for limiting the outward adjustment of the hood.

In order to facilitate the transportation of 35 my improved device, I find it of advantage to provide the end walls of the container 1 with the hand clasp 21 of any ordinary or preferred arrangement.

From the foregoing description, it is thought to be obvious that an egg tester constructed in accordance with my invention is 40 of an extremely simple and comparatively inexpensive nature and is particularly well adapted for use by reason of the convenience and facility with which it may be assembled, and it will also be obvious that my invention is susceptible of some change and modification without material departure from the principles and spirit thereof and for this reason I do not wish to be understood as limiting myself to the precise arrangement and formation of the several parts herein shown in carrying out my invention in practice.

I claim:

55 1. An egg tester comprising a container provided with supports intermediate its height, a tray removably positioned within the container and adapted to rest upon the supports, a table yieldably supported by the tray thereabove, a source of electrical energy within the container at a point below the supports, a lamp carried by the tray, the table at points above the lamp being provided with egg receiving openings, an electrical connection between the lamp and the 60

source of electrical energy, coacting contacts interposed in said electrical connection, one of said contacts being carried by the tray and the second contact being carried by the table, said contacts being adapted to engage upon depression of the table under the influence of the eggs positioned within the openings thereof, the upper end of the container being open, and a hood adapted to overlie the open end of the container, said hood being provided with an opening to permit access within the container when the hood is in closed adjustment. 70 75

2. An egg tester comprising a container provided with supports intermediate its height, a tray removably positioned within the container and adapted to rest upon the supports, a table yieldably supported by the tray thereabove, a source of electrical energy within the container at a point below the supports, a lamp carried by the tray, the table at points above the lamp being provided with egg receiving openings, an electrical connection between the lamp and the source of electrical energy, coacting contacts interposed in said electrical connection, one of said contacts being carried by the tray and the second contact being carried by the table, said contacts being adapted to engage upon depression of the table under the influence of the eggs positioned within the openings thereof, the upper end of the container being open, and a hood adapted to overlie the open end of the container, said hood being provided with an opening to permit access within the container when the hood is in closed adjustment, said hood being substantially the shape of an inverted V in cross section, the lower marginal portion of one side wall of the hood being cut-away lengthwise thereof. 80 85 90 95 100 105

3. An egg tester comprising a container provided with supports intermediate its height, a tray removably positioned within the container and adapted to rest upon the supports, a table yieldably supported by the tray thereabove, a source of electrical energy within the container at a point below the supports, a lamp carried by the tray, the table at points above the lamp being provided with egg receiving openings, an electrical connection between the lamp and the source of electrical energy, coacting contacts interposed in said electrical connection, one of said contacts being carried by the tray and the second contact being carried by the table, said contacts being adapted to engage upon depression of the table under the influence of the eggs positioned within the openings thereof, the upper end of the container being open, and a hood adapted to overlie the open end of the container, said hood being provided with an opening to permit access within the container when the 110 115 120 125 130

hood is in closed adjustment, said hood being substantially the shape of an inverted V in cross section, the lower marginal portion of one side wall of the hood being cut-away lengthwise thereof, the lower marginal portion of said side wall being provided with a recess.

In testimony whereof I hereunto affix my signature in the presence of two witnesses.

ARTHUR L. SCHOOLER.
